DUAL MICROPHONE SYSTEM

Warren B. Bruene, Cedar Rapids, Iowa, assignor
to Collins Radio Company, Cedar Rapids,
Iowa, a corporation of Iowa

Application February 14, 1948, Serial No. 8,399

7 Claims. (Cl. 179—1)

1

This invention relates to microphone-amplifier systems and more particularly to such systems for use with microphones of different characteristics.

A principal object of the invention is to provide a microphone-amplifier system which is capable of producing substantially uniform output regardless of whether the input is provided from a carbon microphone or a dynamic microphone.

Another object is to provide a microphone-amplifier system wherein the amplifier is arranged to be driven either by a dynamic microphone or a carbon microphone, together with switching and circuit arrangements for rendering the output of the amplifier substantially uniform for either of the types of microphones that is used.

A feature of the invention relates to an amplifier which is adapted to be driven either by a dynamic microphone or a carbon microphone, together with adjustable circuit arrangements common to both microphone inputs for producing substantially uniform output from the amplifier regardless of which microphone is being used.

A further feature relates to the novel organization, arrangement and relative interconnection of parts which cooperate to provide an improved dual microphone amplifier system.

Other features and advantages not particularly enumerated will be apparent after a consideration of the following detailed descriptions and the appended claims.

In certain types of communication apparatus, for example in voice frequency amplifiers, modulators and the like, it is sometimes necessary to derive the input signals either from a dynamic microphone or a carbon microphone. One of the drawbacks to the use of these two different types of microphones is that they require different amplifier gains in order to produce the same output from the amplifier. The dynamic type microphone requires a greater gain than does the carbon microphone, but the carbon microphone requires a separate source of power such as a battery in order to render it operative.

There is shown in the drawing a microphone amplifier system wherein the amplifier may be driven by either type of microphone while at the same time preserving substantial uniformity of output regardless of which microphone is used. For this purpose, there is provided an amplifier tube 1 which may be of any well-known type, and while the drawing shows this tube as of the triode indirectly heated cathode type, it will be understood that any other well-known type of amplifier tube may be employed. The dynamic microphone 2 is connected across the control grid 3 and the

2

cathode 4 of tube 1, a suitable high resistance grid leak 5 being provided across the grid and cathode. The direct current supply for the plate or anode 6 is represented schematically in the drawing by the battery 7, the negative terminal of which is grounded and the positive terminal of which is connected to the primary winding 8 of an audio frequency coupling transformer 9 and thence to the plate 6. The secondary winding 10 of this transformer can then be connected to any suitable additional amplifier stage as may be required. The necessary bias between the grid 3 and cathode 4 is achieved by means of the usual cathode bias resistor 11 connected between the cathode 4 and ground, this bias resistor 11 being shunted by the condenser 12, under control of the single-pole single-throw switch 13, which is closed when the dynamic microphone 2 is being used. Under these conditions, the tube 1 acts in the well-known manner to amplify the signals applied to the grid 3 from the dynamic microphone.

When it is desired to use the carbon microphone 14, the switch 13 is opened. It will be observed that a part of the direct current from the power source 7 flows to ground through the resistors 15, 16, in series, which therefore act as voltage dividers. The microphone 14 is connected across the resistor 16 to supply the necessary power for that microphone. The sound waves incident upon the microphone 14 produce audio frequency variations which are coupled through the adjustable resistor 17 and thence through the condenser 12 to the cathode 4, thus driving the cathode 4 in accordance with these audio frequency signals. Thus, the condenser 12 which normally would function as the by-pass condenser for resistor 11 as above described, now functions as a direct current blocking condenser between the carbon microphone 14 and the driven cathode 4. This method of driving the tube 1 by variation of the cathode potential 4, results in lower gain from the tube 1. However, this is a desirable effect in the system as disclosed, since normally the carbon microphone 14 would produce a higher audio output at its terminals for a given sound wave incident thereon, as compared with the same sound wave incident upon the dynamic microphone. By adjusting the resistor 17, it is possible to maintain the output from transformer 9 substantially uniform regardless of which of the two microphones is being employed.

When the system is being used, it is not necessary to adjust the resistor 17 for each transmission. It may be initially set to produce the same

gain for a given intensity of sound upon each microphone and when once set, it can remain in its adjusted position. Consequently, all that is necessary to switch from the dynamic microphone input to the carbon microphone input is to open the switch 13. The condenser 12 therefore performs the double function of acting as a by-pass condenser when the dynamic microphone is being used and as a direct current blocking condenser when the carbon microphone is being used.

The expression "dynamic microphone" as employed in the specification and claims means any microphone which does not require a separate battery or power source to render it effective; and includes any of the well-known types of microphones which generate a voltage in response to impinging sound waves, e. g., crystal microphones, ribbon microphones, moving coil-magnet microphones, velocity microphones and the like.

While one particular embodiment has been described, it will be understood that various changes and modifications may be made therein without departing from the spirit and scope of the invention.

What is claimed is:

1. A microphone amplifier system, comprising a grid-controlled amplifier tube, a microphone of the dynamic type, another microphone of the type which requires a local source of direct current power, and a two-position switch for operatively connecting either microphone to the input of said amplifier while maintaining the amplifier output substantially uniform for a given sound input regardless of which microphone is being used, and circuit connections operative when said switch is closed in one position to connect said other microphone only capacitively to the cathode of said amplifier tube.

2. A microphone amplifier system, comprising a grid-controlled tube, a microphone of the type which generates voltage in response to impinging sound waves, a carbon microphone which varies the resistance in an associated direct current supply circuit, means connecting the first-mentioned microphone to drive the control grid of said tube, means including a series coupling condenser 4 connecting the second-mentioned microphone to drive the cathode of said tube, and switch means for operatively connecting either of said microphones with said amplifier.

3. A microphone amplifier system, comprising a grid-controlled amplifier tube, a microphone of the dynamic type, a microphone of the non-dynamic type, a cathode bias resistor for said tube, a by-pass condenser for said resistor, a two-position switch, circuit connections effective with said switch in one position for operatively isolating the non-dynamic microphone from the amplifier and connecting said condenser across said resistor, and other circuit connections effective when said switch is in another position for operatively connecting said non-dynamic micro-

phone to the cathode of said amplifier through said condenser while removing said condenser from across said resistor.

4. A microphone amplifier system, comprising a dynamic microphone, a non-dynamic microphone, a grid-controlled amplifier tube for both microphones, said tube having a cathode bias resistor, means including another resistor and a condenser connecting said non-dynamic microphone in series between said cathode and ground, a two-position switch, circuit connections effective in one position of said switch to isolate said non-dynamic microphone from said cathode and simultaneously connecting said condenser in shunt to said bias resistor and other circuit connections effective when said switch is in another position to disconnect said condenser from said bias resistor.

5. A microphone amplifier system, comprising a dynamic microphone, a non-dynamic microphone, a grid-controlled amplifier tube for both microphones, a switch for selectively rendering either of said microphones effective on said amplifier, a cathode bias resistor and shunt condenser for said tube, means effective with the switch in one position to drive the grid of said tube by the output of said dynamic microphone, means effective with the switch in another position to drive the cathode of said tube by the output of said non-dynamic microphone, said switch when in said other position disconnecting said condenser from across said bias resistor.

6. A microphone amplifier system, comprising a pair of microphones of different signal outputs, a grid-controlled amplifier tube for both microphones, a bias resistor connected between the cathode of said tube and ground, means connecting one microphone across the grid and ground, a condenser, a two-position switch effective in one position to bridge said bias resistor by said condenser and effective in another position to disconnect said condenser from across said resistor, and means connecting the other microphone effectively in series with said condenser and cathode when said switch is in said other position.

7. A microphone amplifier system, according to claim 6 in which an adjustable resistor is connected in series between said other microphone and said condenser for equalizing the outputs of the amplifier regardless of which microphone is being used.
